United States Patent Office

Des. 212,793
Patented Nov. 19, 1968

212,793

TRANSPARENCY STORAGE UNIT

Stephen B. Smith, Dayton, and Karl F. Rigg, Bellbrook, Ohio, assignors to The National Cash Register Company, Dayton, Ohio, a corporation of Maryland

Filed Dec. 8, 1967, Ser. No. 9,709

Term of patent 14 years

(Cl. D87—1)

FIG. 1

FIG. 2

FIG. 3

FIG. 4

FIG. 5

FIG. 1 is a front perspective view, taken from the right side, of a transparency storage unit, showing our new design;

FIG. 2 is a rear perspective view, taken from the left side thereof;

FIG. 3 is a top plan view thereof;

FIG. 4 is a right side elevational view thereof; and

FIG. 5 is a front elevational view thereof.

The dominant features of our design reside in the full-line portions of the drawings.

We claim:

The ornamental design for a transparency storage unit, as shown and described.
